CLAIM

The ornamental design for a display screen or portion thereof with graphical user interface, as shown and described.

DESCRIPTION

The file of this patent contains at least one drawing/photograph executed in color. Copies of this patent or patent application publication with color drawing(s) will be provided by the Office upon request and payment of the necessary fee.

The sole FIGURE is a front view of a display screen or portion thereof with graphical user interface showing our new design.

The outer perimeter shown in broken lines in the drawing FIGURE depicts the display screen or portion thereof and forms no part of the claimed design.

(Continued)

The remaining broken lines in the drawing FIGURE show portions of the graphical user interface that form no part of the claimed design.
